UNITED STATES PATENT OFFICE.

EDWARD J. POPE, OF ST. JOSEPH, MICHIGAN, ASSIGNOR TO MULLEN & POPE SCREEN COMPANY, A CORPORATION OF MICHIGAN.

REVOLVING SCREEN.

1,399,653.

Specification of Letters Patent.

Patented Dec. 6, 1921.

Application filed July 24, 1919. Serial No. 313,070.

To all whom it may concern:

Be it known that I, EDWARD J. POPE, a citizen of the United States, residing at St. Joseph, in the county of Berrien and State of Michigan, have invented certain new and useful Improvements in Revolving Screens; and I do hereby declare the following to be a full, clear, and exact description of the invention, such as will enable others skilled in the art to which it appertains to make and use the same.

This invention relates to certain improvements in screens, particularly of the type for treating pulp.

The invention has for its object to provide for effecting the screening or sifting of the pulp as it is taken up or elevated within a vat upon a rotatable slotted or perforated cylinder or screen, the pulp being at the same time subjected to an alternate suction and pressure action for effecting the elevating of the pulp upon the rotatable cylinder, thus providing not only for the cleaning of the pulp, but also against the clogging or choking of the screen openings or slots, a perfect clearance action being thereby provided for the ready outward and inward passage of the otherwise detained portion of the pulp through said slots or openings.

As further object of the invention is to carry out the aforesaid ends in an effective, simple and inexpensive manner, while still further objects thereof will be made apparent from the following description or disclosure of the invention.

The invention therefore consists of certain instrumentalities and features of construction substantially as hereinafter fully disclosed and defined by the appended claims.

In the accompanying drawings is illustrated the preferred embodiment of my invention, wherein it will be understood that various changes and modifications as to the detailed construction and arrangement of parts may be made without departing from the spirit or scope of the invention as embraced in the appended claims.

In the drawings:

Figure 1 is a partly vertical longitudinal, sectional, and side elevational view of my invention;

Fig. 2 is a transverse vertical sectional view taken on line 2—2 of Fig. 1.

In practising my invention, I provide a

suitable vat or receptacle 1, superposed or mounted upon a frame or support A which may be constructed in any way most convenient and adapted to conserve the ends in view.

The vat or receptacle 1, into which the pulp is fed from an auxiliary receptacle or feed box 2, also secured upon the support A, has rotatably mounted therein a screening cylinder 3, upon a central longitudinal shaft 4 carrying or fixed to said screening cylinder and journaled upon suitable bearings 5, secured to said support. The vat or receptacle 1 has an end outlet compartment 1^a for the discharge of the pulp, passing out through an end of the screen, which has been screened and cleaned.

A partition member 6, secured within the vat to the sides and bottom thereof, extends upwardly about the center of the cylinder and conforms to the periphery or circumference of the screening cylinder 3, and subdivides the vat into compartments 7.

The screening cylinder has its periphery covered with plates 8 suitably applied and secured thereto and entirely encompassing the same. Said plates are each provided with numerous closely disposed elongated perforations or slots 9, extending preferably in lines parallel with the axis of the cylinder, whereby they are adapted to allow more readily for the passage of the pulp as the cylinder is revolved, as is believed clearly apparent. These slots or perforations are also preferably arranged in symmetrical groups, the individual slots or perforations thereof alining each other as shown, thereby having the tendency to also obviate a clogging or congestion action of the pulp.

A piston cylinder 10 is arranged in connection with the vat, either vertically or horizontally, at the side or under the vat, and is provided with a piston 11 whose actuating rod 11^a is suitably packed in the usual manner, as at 11^b, at one end of the cylinder, and is adapted to be actuated for imparting a reciprocating movement to the piston, preferably by means of a connecting rod or pitman 12 suitably coupled to said piston-rod and to a cross-head 13, in turn connected to a crank shaft 14 suitably actuated by a pulley 15, the latter being driven by a motor-driven belt, (not shown) or otherwise. The crank shaft 14 is supported in a suitable bearing 15^a suitably supported

upon the frame A or otherwise. The piston cylinder 10 is provided in its upper surface with two passages or ports 16, and around said ports are provided upwardly flared flanges 16^a forming hopper-resembling mouths therefor, for extending the suction or pressure area, as will presently more fully appear. These ports or passages are positioned in vertical alinement with openings or passages 1^b, 1^b, in the vat bottom, so as to provide for producing within the compartments 7 of the vat an alternate suction and pressure therethrough when the piston 11 is actuated.

15 The screening cylinder shaft 4 is preferably driven by means of a worm wheel 17 secured thereon, said worm wheel being preferably in mesh with and rotated by a worm 18 supported upon brackets 19 secured to the frame A, said worm being in practice belted to and driven by pulley 15 on crank shaft 14.

In operation, the pulp preliminarily placed or delivered into the auxiliary receptacle or box 2, is in turn fed into the vat 1 in suitable quantities, which pulp is subjected to an alternate suction and pressure action by means of piston 11, which action raises the pulp in the vat and forces a part 25 of the pulp through the slots or perforations in the screen plates 8. As the pulp is lowered in the vat on the return stroke of the piston 11, it draws back the pulp which has partly passed through the slots in the plates 30 8, thus preventing the slots from becoming clogged. The cleaned portion of the pulp is passed out of the open end of the cylinder 3 and goes to the paper making machine. As 35 above indicated, it will be observed that during the suction action of the piston a perfect clearance is provided through the pulp-screening slots or openings of the cylinder or screen, thus providing, as stated, against the clogging or choking action. The uncleared 40 pulp or residue passes out through passages in the bottom of the vat for further treatment.

Having described my invention, what I claim and desired to secure by Letters 50 Patent is:

1. A screen or sifter, including a vat having an outlet at one end, a rotatable screen positioned in said vat and having a numerously slotted or perforated perimeter, a com- 55 mon-pressure-exerting and suction generat-

ing means coöperative with said rotatable screen, and means subdividing said vat exteriorly of said screen, whereby the material in said vat is alternately forced upwardly and drawn downwardly through the 60 slots in the screen plates of said screen.

2. A screen or sifter, including a vat having an outlet at one end, a rotatable screen positioned in said vat and having a numerously slotted or perforated perimeter, a common pressure-exerting and suction-generating means coöperative with said rotatable screen and comprising a reciprocating piston working in a cylinder in communication with said vat, and means subdividing said 70 vat exteriorly of, and at a point intermediate of the ends of said cylinder.

3. A screen or sifter, including a vat having an outlet at one end, a rotatable screen positioned in said vat and having a numerously slotted or perforated perimeter, a common pressure-exerting and suction-generating means coöperative with said rotatable screen and comprising a reciprocating piston working in a cylinder in communicating 80 with said vat, means subdividing said vat exteriorly of, and at a point intermediate of the ends of said rotatable screen, means for actuating said screen, and means for actuating said piston.

4. A screen or sifter, including a vat having a plurality of compartments and an outlet at one end, a screen arranged to rotate within said compartments and having its perimetrical surface provided with a plurality of elongated slots, with their axes extending in lines parallel with the axis of the screen, and means for forcing material upwardly and downwardly alternately in the compartments of said vat and through said 95 slots.

5. A screen or sifter, including a vat having a plurality of compartments and an outlet at one end, a screen arranged to rotate within said compartments, and having its perimetrical surface formed of plates each provided with a plurality of slots arranged in groups, the individual slots of each group being in alinement with each other, and means for forcing material upwardly and downwardly alternately in the compartments of said vat and through said slots.

In testimony whereof, I affix my signature.

EDWARD J. POPE.
